UNITED STATES PATENT OFFICE

160,056

COFFEE SERVER

Edwin L. Beckwith, West Newton, Mass., assignor to Beckwith Manufacturing Company, Dover,
N. H., a corporation of New Hampshire

Application December 16, 1949, Serial No. 6,659

Term of patent 14 years

(Cl. D44—26)

To all whom it may concern:

Be it known that I, Edwin L. Beckwith, a citizen of the United States, residing at West Newton, in the county of Middlesex and Commonwealth of Massachusetts, have invented a new, original, and ornamental Design for a Coffee Server of which the following is a specification, reference being had to the accompanying drawing forming a part thereof, in which:

Fig. 1 is a plan view of a coffee server showing my new design, and

Fig. 2 is a side elevational view thereof.

The two sides of the coffee server are similar in appearance.

I claim:

The ornamental design for a coffee server, as shown and described.

EDWIN L. BECKWITH.
